(57) **CLAIM**

The ornamental design for a LED light bulb, as shown and described herein.

DESCRIPTION

FIG. 1 is a front, top perspective view of a LED light bulb, according to one example of the present disclosure, including an at least partially translucent bulb surface revealing interior elements with the LED light bulb in a “powered-off” state; FIG. 2 is a front, top perspective view of a LED light bulb, according to one example of the present disclosure, including an at least partially translucent bulb surface revealing interior elements with the LED light bulb in a “powered-on” state; FIG. 3 is an exploded view illustrating interior elements of the LED light bulb of FIG. 1, according to one example of the present disclosure;

FIG. 4 is a front plan view of the LED light bulb of FIG. 2; FIG. 5 is a back plan view of the LED light bulb of FIG. 2; FIG. 6 is a left side view of the LED light bulb of FIG. 2; FIG. 7 is a right side view of the LED light bulb of FIG. 2; FIG. 8 is a top plan view of the LED light bulb of FIG. 2; and, FIG. 9 is a bottom plan view of the LED light bulb of FIG. 2. The broken lines in the drawings illustrate portions of the LED light bulb which form no part of the claimed design.

1 Claim, 9 Drawing Sheets
